ATTORNEY.

Edwin J. Larson

UNITED STATES PATENT OFFICE.

GEORGE S. McFARLAND, OF COLUMBUS, OHIO.

CAP FOR FILL PIPES FOR TANKS OR CONTAINERS.

Application filed May 25, 1922. Serial No. 563,635.

My invention relates to caps for fill-pipes for tanks or containers where it is desirable to close the inlet thereto and, more particularly, to an improvement in caps for fill-pipes for gasoline or oil tanks and radiators for automobiles.

Heretofore, in connection with gasoline or oil tanks and radiators for automobiles, the usual method of closing the inlet thereto has been by providing a screw cap adapted to fit the fill-pipe. It is a well known fact that by the use of this type of cap for the purpose stated, much time is required to remove and replace same; in removing and applying the cap, the threads may become stripped or otherwise distorted; the cap may be removed for the purpose of filling the tank or container and not replaced, permitting dust, dirt and other foreign objects to get into the tank as well as increasing the danger of fire and explosion; and no means are provided for automatically releasing any pressure which may accumulate in the tank or container due to the expansion of the fluid contained therein, all of which are very objectionable features.

An object of my invention is to provide a cap of the above type of such form that a quick opening and closing of the inlet to the tank or container may be effected thereby reducing to a minimum the danger of dust, dirt, et cetera, getting into the tank or container, and lessening the possibility of fire and explosion.

Another object is to provide a cap for fill-pipes for tanks or containers for automobiles which permits opening of the inlet to the tank or container without detaching any of the parts thereof, thereby eliminating the possibility of the cap being detached and left off by a person filling the tank.

Another object is to provide means for sealing the cap in its closed position so as to prevent the admission of dust, dirt, et cetera, to the tank or container inlet when same is closed.

Still another object is to provide means whereby excess pressure occasioned by the expansion of the fluid contained in the tank or container is allowed to pass off freely as it accumulates, thereby preventing any danger of the tank or container being subjected to undue strains.

Other and further objects of the present invention will in part be obvious and in

part be pointed out hereinafter in the specification following by reference to the accompanying drawing, wherein like parts are represented by like characters throughout the several figures of the said drawing. 60

In the drawing—

Figure 1 is a plan view of my invention.

Figure 2 is a side elevation showing the position of the parts of my invention in their closed position. 65

Figure 3 is a vertical sectional view on the line 3—3 of Figure 1.

Referring more particularly to the drawing, my invention may consist of a body 1, which is adapted to be attached to the fill-pipe of a tank or container (not shown) of an automobile by any suitable means, preferably by the threaded portion as shown at 2 (Figure 3). The body 1 is provided with a top portion 3, the surface of which is inclined slightly upward. A filling opening 4 is provided in the top portion 3 through which access is had to the fill-pipe of the tank or container (not shown). 70 75

On the outer periphery of the top 3 of 80 and integral with the body 1 is a pronged hinge member 5 having drilled holes 6 through same adapted to receive the hinge pin 7. A cover 8 is hingedly mounted upon the body 1 and adapted to cover the filling opening 4 when in its normal closed position, this being effected by means of the hinge pin 7 and the bifurcate hinge member 9, integrally projecting therefrom and adapted to be held in place between the prongs of the body hinge member 5 by the hinge pin 7. The cover 8 is slightly convexed as shown in Figure 2, the central portion of its top terminating in an integrally carried lifting lug 10 which permits of a 85 convenient means for applying the hand when it is desired to move the cover 8 to open the filling opening 4. It may also be noted here that the cover 8 may be raised, if only slightly, by fluid pressure acting on its under side which will be mentioned hereinafter. 90 95

Mounted upon the hinge pin 7 between the prongs of the cover hinge member 9 is a coil spring 11 (Figure 1) which is so constructed that its end coils, instead of terminating within the circumference of the coils of the spring, extend outward in practically straight lines at less than 90° so that when assembled upon the hinge pin 7 the end 12 100 105 110

extends downward from the hinge pin 7, bearing against the outer surface of the body 1 as shown in Figures 1 and 3, and the opposite end 13 extends towards the center 5 of the cover 8 at approximately right angles to the projecting end 12 and bears upon the cover 8, being held in place on same by inserting the end in a hole 14 in the lug 10.

With the spring 11 constructed and placed 10 as above, the end 13 bearing on the cover 8 exerts a downward force tending to hold the cover 8 closed over the filling opening 4 and tends to oppose the opening of the same. By this construction it is readily 15 seen that when pressure is applied by the hand or otherwise to move the cover to open the fill opening 4 and the said cover is in its open position, the withdrawing of such pressure permits the spring 11 to quickly 20 close the cover 8.

With the above construction it is highly desirable that a tight joint be maintained 25 between the cover 8 and the top 3 of the body 1 at all times when the cover 8 is closed in order to prevent the admission of dust, dirt, et cetera, to the interior of the tank or container and also loss of the fluid contained therein. To accomplish this the gasket 15 is provided and adapted to be 30 attached and held in place on the under side of the cover 8 by being interposed between the cover 8 and a washer 16 which is, in turn, secured to the cover 8 by a screw 17. By the use of this gasket 15 and due 35 to the resilience of the spring acting on the cover 8, a tight seal is formed between the cover 8 and the top 3 of the body 1 when the cover 8 is in closed position.

The gasket 15 may be composed of any 40 suitable material which offers the required elasticity and the necessary resistance to the deteriorating action of gasoline, oils, heat, et cetera, but in connection with the above I show and employ preferably a felt material.

In connection with the use of tanks or 45 containers for gasoline or oil, it is customary to provide an opening in the cap to take care of the conditions resulting from the expansion and contraction of the gases in the tank or container; but in certain instances, such as the tank or container being subjected to excessive heat, the above stated opening does not carry off the excessive accumulated gas quickly enough, resulting in 50 the tank or container being subjected to undue strains. In connection with my invention, I likewise provide an opening 18 (Figure 3) in the top 3 of the body 1 but in addition to that, with my invention, if the pressure in the tank or container exceeds 55 a certain predetermined amount, the excessive pressure acting on the cover 8 will raise same from its seat until the excess pressure 60 has escaped.

It will be seen that I have provided a novel and decidedly simple cap for a tank or container inlet which is of amply strong construction and so tensioned that it will always be held securely in normal closed position except when it is forcibly held open for insertion of the filling means or by excess expansion of the fluid in the container. 70

It will also be noted that opening and closing of the inlet to the tank or container 75 is accomplished quickly and easily without the manipulation of any threaded portions; it is not necessary to remove any of the parts thereof to permit filling of the tank or container; and if any excess pressure accumulates due to the expansion of the fluid contained in the tank or container, the cover will be forced open against the pressure of the spring whereby said pressure is automatically released. 80

It will be further noted that in inserting the nozzle of the filling means into the inlet of the container, the cap is so positioned and tensioned as to securely hold this nozzle in a fixed position during the filling 90 operation.

In the various fields in which my invention may be employed, the details of construction may necessitate alterations falling within the scope of what is claimed. 95

Having described my invention, what I claim as new and useful and desire to secure by Letters Patent is:

1. A cap for automobile container inlets comprising a body having an opening therethrough, a cover for said body, and means carried by outwardly extending members integral with said cover and said body for yieldably holding said cover closed against normal pressure of fluid in the container but allowing the cover to be opened by any abnormal pressure in the container. 100

2. A cap for automobile container inlets comprising a body, an outwardly opening cover for said body, members extending outwardly from said cover and said body and integral therewith, said members being pivotally connected at their outward extremities by a pin, a spring carried by said pin and said outwardly extending members so as to oppose the opening of said cover, and an upwardly extending handle member integral with said cover and carrying one end of said spring. 110

3. A cap for automobile container inlets comprising a detachable body having an opening in the top thereof, an outwardly opening cover for closing said opening, said cover carrying a closure sealing means and having an up-standing handle member integral therewith, lugs integral with and projecting from said cover having a hinge pin mounted between the ends thereof, a spring mounted on said pin, one end of said spring engaging the said handle member. 120

125

4. In a cap for automobile container inlets, a body having an opening in its top and an outwardly opening cover for closing said opening, said cover comprising a closure sealing means, an exteriorly upstanding handle member integral with said cover, a hinged member integral therewith having a hinge pin mounted in the same, and a spring mounted on said pin, one end of said 10 spring engaging in a socket in the said handle member.

5. A cap for container inlets comprising an apertured threaded body portion having a bracket, an outwardly opening lid having 15 handle and integral portions pivoted to said bracket, and a spring secured to said pivot, said spring having parts bearing against said body portion and the handle of said lid

for normally maintaining said lid in closed relation to the aperture in said body portion. 20

6. A cap for container inlets comprising a body portion having means for attaching it to the fill pipe of a container and an opening adapted to register with said fill pipe, an outwardly opening lid having a handle 25 with a recess therein and portions pivoted to said body portion and a spring on said pivot having a portion engaging with the recess in the handle of said lid and a portion bearing against said body portion, said 30 spring serving to maintain said lid in closed relation to the opening in said body portion.

In testimony whereof I hereby affix my signature.

GEORGE S. McFARLAND.
